[57] CLAIM

The ornamental design for a Christmas tree light frame, as shown and described.

DESCRIPTION

FIG. 1 is a side elevation view of the Christmas tree light frame showing my new design. The front, rear and side elevation views are all identical.

FIG. 2 is a top plan view thereof;

FIG. 3 is an enlarged top plan view of a cap member of the frame;

FIG. 4 is a side elevation view of the cap member of FIG. 3;

FIG. 5 is a cross sectional view taken across the lines 5—5 of FIG. 1;

FIG. 6 is an enlarged cross sectional view taken across the lines 6—6 of FIG. 5;

FIG. 7 is an enlarged cross sectional view taken across the lines 7—7 of FIG. 1; and,

FIG. 8 is a top plan view further illustrating, in broken lines, wiring and electric lamps mounted on the frame, and forming no part of my design.
